RETHREADING TOOL

Alex Mackiet, Spokane, Wash.

Application October 19, 1944, Serial No. 559,347

7 Claims. (Cl. 10—1)

This invention relates to a rethreading tool and it is one object of the invention to provide a tool by the use of which threads of a bolt which have become marred may be recut and thus allow a nut to be easily screwed upon the bolt.

Another object of the invention is to provide a rethreading tool which may be held in a person's hand and applied to a bolt for recutting the thread of the bolt.

Another object of the invention is to provide a rethreading tool having a body formed with an opening tapered toward its lower end where a jaw is removably and reversibly mounted so that either a large or a small bolt-receiving seat may be presented in position for use.

Another object of the invention is to provide the tool with an upper jaw consisting of a block mounted at the top of the body and carrying a cutter which is shiftable longitudinally through a bore formed through the block and has swiveled connection with a pressure screw threaded into the bore through the upper end thereof.

Another object of the invention is to provide an upper jaw of the block which may be removed from the head at the upper end of the body when necessary and in addition provide improved means for shifting the jaw longitudinally into position for gripping a bolt disposed between the jaws.

In the accompanying drawing.

Fig. 1 is a front view of the improved rethreading tool.

Fig. 2 is a transverse sectional view on the line 2—2 of Fig. 1.

Fig. 3 is a longitudinal sectional view on the line 3—3 of Fig. 1.

Fig. 4 is a front view of a modified form of rethreading tool.

Fig. 5 is a sectional view on the line 5—5 of Fig. 4.

Fig. 6 is a fragmentary view of the cutter and the pressure screw swiveled to its upper end.

This improved rethreading tool is preferably formed as illustrated in Figs 1 through 3 of the drawing and has a body 1 formed of strong metal. This body has an opening 2 formed therein which tapers toward its lower end and in its tapered lower end portion is disposed a block 3 constituting a lower jaw. This jaw is substantially diamond-shaped to provide diagonally extending upper and lower edge faces and allow the block to be set in place with either the large bolt-receiving recess 4 disposed upwardly in position for use or the small recess 5 in position for use. The

recesses 4 and 5 constitute seats to receive a bolt 6 which is to have its thread recut and the jaw will be applied in accordance with the size of the bolt. A screw 7 having a turning head 8 is rotatably passed through an opening 9 formed at the lower end of the body and engaged in a threaded opening 10 formed through the block between the seats 4 and 5, and when this screw is turned in a tightening direction, it draws the block or jaw downwardly against the downwardly converging inner side edge faces of the side portions of the body and very firmly secures the block.

The upper portion of the body is formed with a head 11 having an opening 12 formed vertically through it to slidably receive a block or upper jaw 13 having its lower end formed with a recess 14 into which the bolt fits as shown in Fig. 1. A pocket 15 which is open at its upper end and along its outer side and has its wall threaded, is formed along a side of the block or upper jaw 13 and this pocket registers with a pocket 16 formed longitudinally of the head 11 at a side of the opening 12. This pocket 16 is open along one side and at its upper end but is unthreaded so that an adjusting screw 17 may turn freely in pocket 16. This screw has a turning head 18 at its upper end and, in spaced relation to its lower end, is formed with a circumferentially extending groove 19 to receive a set screw 20 which is screwed into an opening 21 formed in the head 11 transversely thereof and has a reduced inner end portion 22' for engaging in groove 19. The adjusting screw meshes with threads of the socket 15 and when it is turned, the block or jaw 13 will be shifted longitudinally into or out of position for gripping the bolt 6 and firmly holding the bolt between the jaws. While it has been stated that the bolt is firmly held between the jaws, it is to be understood that the grip upon the bolt is such that the tool may be turned about the bolt or the tool held in one hand while the bolt is turned with a pair of pliers.

As the bolt is turned, or the tool turned about the bolt, rust or rough places are to be cut from its thread. In order to do so, there has been provided a cutter 22 which is mounted in an opening 23 and at its upper end is formed with a spherical head 24 rotatably engaged in a socket 25 formed at the lower end of a pressure-applying screw 26. The screw 26 has a turning head 27 at its upper end so that it may be readily turned to shift the cutter longitudinally and carries a locking nut 28 by means of which it is secured in a set position with the cutter so engaged in the thread of the bolt that as the tool

is turned about the bolt the threads of the bolt will be cleared of rust or other obstructions.

In Figs. 4 and 5 there has been illustrated a rethreader of a modified construction. In this embodiment of the invention, the body 29 is circular and formed with an opening 30 tapered toward its lower end. A block or lower jaw 31 is removably received in the opening 30 and formed with side flanges 32 which overlap faces of the body along the tapered lower portion of opening 30 and prevent the block from shifting transversely out of the opening. At its top, the body is formed with a socket 33 having threaded walls and from this socket extends an opening 34 located centrally of the socket. A block 35 has its threaded lower portion of shank 36 screwed into the socket 33 and this block is formed with a longitudinally extending bore or passage 37 to slidably receive a cutter 38. The opening 37 is rectangular throughout the major portion of its length so that the cutter will be held against turning, but its upper end portion is threaded for receiving a pressure screw 39 which has its lower portion 40 reduced in thickness and swiveled to the upper end of the cutter by a ball and socket joint 41. A locking nut 42 is carried by the pressure screw to hold the screw and the cutter in adjusted position and, at its upper end, the screw is formed with a turning head 43 by means of which it may be readily turned to shift the cutter longitudinally.

Having thus described the invention, what is claimed is:

1. A rethreading tool comprising a body formed with an opening tapered toward its lower end and having a head at its top, a reversible diamond-shaped block in the tapered lower portion of said body constituting a lower jaw formed with upper and lower V-shaped recesses constituting bolt-receiving seats and a threaded bore between the seats, a screw rotatably passing through an opening in the lower end of said body and engaged in the threaded bore to hold the block in place, said head being formed with a vertical passage and with a pocket at a side thereof, a block constituting an upper jaw slidable vertically through said passage and having a V-shaped bolt-receiving recess at its lower end and a threaded pocket open along one side and confronting the pocket of said head, an adjusting screw in said pocket meshing with threads of the pocket in the upper block for shifting the upper block vertically, said screw being formed with a circumferential groove, a set screw threaded through a side opening in said head and engaged in the groove to rotatably mount the adjusting screw, the upper block being formed with a longitudinal passage threaded from its upper end, a thread cutter shiftable longitudinally through said passage and protruding downwardly therefrom, and a pressure screw threaded into said passage and swiveled to the upper end of the thread cutter.

2. A rethreading tool comprising a body formed with an opening and having a head at its upper end formed with a passage communicating with the opening, a reversible lower jaw in the lower portion of the opening formed with upper and lower bolt-receiving seats, a block slidably vertically through said passage and constituting an upper jaw having a bolt-receiving seat in its lower end, said block being formed with a longitudinal bore threaded from its upper end, a cutter in said bore shiftable vertically

therein and projecting downwardly from the block, a screw threaded into the bore from the upper end thereof and swiveled to the upper end of said cutter, and an adjusting screw rotatably mounted vertically in said head and having threaded engagement with a side portion of said block to adjust the block longitudinally when the adjusting screw is turned.

3. A rethreading tool comprising a body formed with an opening and having a head at its top formed with a vertical passage communicating with the opening, a lower jaw at the bottom of said opening reversibly mounted and having upper and lower seats, a block shiftable vertically through said passage and constituting an upper jaw, means for shifting said block longitudinally and holding the block in adjusted position, said block being formed with a longitudinal passage, a cutter shiftable longitudinally in said passage of said block, and projecting from the lower end thereof, and a screw threaded into the passage of the block through the upper end thereof and having its lower end swiveled to the upper end of said cutter.

4. A rethreading tool comprising a body formed with an opening and having a head at its top formed with a vertical passage communicating with the opening, a lower jaw at the bottom of said opening, an upper jaw shiftable longitudinally through said passage and formed at a side with a socket open along its side and internally threaded, the head of the body being formed at one side of its passage with an open-sided socket registering with the socket of the upper jaw, an adjusting screw rotatably received in the pocket of the body with a portion extending into the socket of the upper jaw and meshing with the threads thereof to shift the upper jaw longitudinally when the screw is turned, said body being formed with a horizontal threaded opening communicating with the open-sided socket of the body, said adjusting screw being formed with an annular groove opposite the inner end of the horizontal threaded opening, a set screw in the horizontal threaded opening having its inner end engaged in the annular groove of the adjusting screw to prevent longitudinal movement of the adjusting screw, and a cutter adjustably carried by said block and projecting downwardly therefrom.

5. A rethreading tool comprising a body formed with an opening, a lower jaw in said opening, the upper portion of said body being formed with a passage, an upper jaw shiftable longitudinally through said passage into and out of said opening, means for shifting said upper jaw and holding same in adjusted position, said upper jaw being formed with a longitudinal bore, a cutter shiftable longitudinally in said bore and protruding downwardly from the upper jaw, and a pressure-applying screw threaded into the bore through the upper end thereof and having its lower end swiveled to the upper end of said cutter.

6. A rethreading tool comprising a body formed with an opening, a lower jaw in said opening, the upper portion of said body being formed with a pocket, a block mounted in said pocket and formed with a longitudinal bore, a cutter shiftable longitudinally in said bore and extending therefrom into said opening, and a pressure screw threaded into said bore through the upper end thereof and swiveled to the cutter.

7. A rethreading tool comprising a body

formed with an opening, a lower jaw in said opening, the upper portion of said body being formed with a threaded socket and with a reduced passage leading therefrom to the opening, a block over said body having a threaded shank screwed into said socket, the block being formed with a longitudinal bore registering with

the reduced passage, a cutter shiftable longitudinally through the bore of said block and through said passage and projecting into the opening of the body, and a pressure screw threaded into said bore through the upper end thereof and swiveled to the cutter.
